G. N. KING

PUMP VALVE

Filed July 7, 1926

Patented Dec. 7, 1926.

1,609,950

UNITED STATES PATENT OFFICE.

GROVER NEGLEY KING, OF SANDERSON, TEXAS.

PUMP VALVE.

Application filed July 7, 1926. Serial No. 120,948.

The present invention relates to improvements in pumps and has reference more particularly to a valve structure for use in conjunction with deep wells.

5 One of the important objects of the present invention is to provide a device of the above mentioned character which will facilitate the lifting of water upwardly from a deep well in a comparatively simple and 10 efficient manner.

A further object of the invention is to provide a device of the above mentioned character which is simple in construction, inexpensive, strong and durable and further 15 well adapted to the purpose for which it is designed.

Other objects and advantages of the invention will become apparent during the course of the following description taken 20 in connection with the accompanying drawing.

In the accompanying drawing forming a part of this application and in which like numerals indicate like parts,

25 Figure 1 is a side elevation of the device embodying my invention showing the working valve in its uppermost open position, the standing valve being closed.

Figure 2 is a vertical sectional view 30 through the device showing the working valve in its lowermost position with the same closed, the standing valve being shown open.

Figure 3 is a transverse section taken 35 approximately on line 3—3 of Figure 2 looking in the direction of the arrows, and

Figure 4 is an enlarged detail of the connection between the spool of the standing valve and the slidable rod associated therewith.

In the drawing wherein for the purpose of illustration is shown the preferred embodiment of my invention, the numeral 1 designates a cylinder, and arranged within 45 the lower end thereof is the standing valve designated generally by the numeral 2. The standing valve comprises a body portion 3 having annular grooves formed therein to receive the packing rings 4 which engage 50 the inner wall of the cylinder in the manner as clearly shown in Figure 2. A central outlet opening 5 is formed in the top of the body portion 3 of the standing valve 2, it being understood of course that the body 55 3 is hollow. An enlarged inlet opening 6 is provided in the bottom of the body por-

tion 3 and the same extends around the tubular guide 7, the purpose of which will be hereinafter more fully described. The supporting means for the tubular guide 60 member 7 is shown at 8 with reference more particularly to Figure 3.

An elongated tube or sleeve 9 has its upper end extending through the tubular guide member 7 and through the outlet 5 65 formed in the top of the body portion 3. The lower end of this tube or sleeve is closed as illustrated at 10 in Figure 1 of the drawing and adapted to extend downwardly into the well for an appreciable distance. This 70 tube or sleeve 9 is of such diameter as to be free to slide through the head or body portion 3 of the standard valve 2.

The upper end of the slidable tube or sleeve 9 is flanged as illustrated at 11 and 75 extending from the flanged upper end of this tube is the threaded extension 12.

Adapted to form a valve or closure for the outlet 5 formed in the top of the hollow body 3 is the spool like member 13, the same having its lower end threaded on the externally threaded extension 12 formed on the upper end of the tube or sleeve 9. A suitable washer 14 is interposed between the flange 10 and the bottom of the spool 13 in the manner clearly shown in Figure 4 and this washer seats on the top of the body portion for preventing any leakage of the water at the outlet 5 when the tube 9 and the spool-like valve 13 are in their 80 lowermost positions.

Figure 5 is provided on the top of the body 3 for the valve like spool 13 for the purpose of limiting the upward sliding movement thereof.

The present invention further includes a working valve designated by the numeral 16, the same being disposed within the cylinder 1 above the standing valve 2 which is adapted for reciprocating movement within the cylinder in the manner to be presently described. The working valve comprises a hollow body portion 17 which is provided with an outlet opening 18 in the top thereof, the bottom of the body being open as is clearly shown in Figure 2. Suitable packing rings 19 extend circumferentially around the body and are disposed within annular grooves provided therefor in the body. A cage 20 is arranged on the top of the body 17 of the working valve 16 and adapted for operation with the cage 20 is 100 105 110

the spool 21 which forms a closure valve for the outlet opening 18 formed in the top of the body 17.

An elongated rod 22 is secured at its upper end to the upper spool 21 and this rod extends downwardly through a suitable bushing 23 provided therefor in the upper central portion of the spool 13, and the lower end of this rod extends downwardly into the elongated sleeve or tube 9. A head 24 is formed on the lower end of the rod and the same is operable within the tube or sleeve 9 and is further of such diameter as to engage the inner wall of said tube as is clearly shown in Figure 1.

An operating rod or shaft 25 extends downwardly into the top of the cylinder 1 and is secured at its lower end to the top of the cage 20 and provides a means whereby the working valve 16 will be reciprocated within the cylinder 1. The upper end of this rod or shaft 25 is adapted to be actuated by appropriate means (not shown) and which is further well known in the art.

With the parts arranged as shown in Figure 1 of the drawing, the spool 13 is seated on the top of the body 3 of the standing valve 4, thus closing the outlet 5 and preventing any water entering the lower portion of the cylinder. With the spool 21 open or rather disengaged from the top of the hollow body 17 so that the outlet opening 18 is uncovered, the water which is in the cylinder 1 between the standing valve and the working valve will be permitted to flow upwardly through the working valve and the cylinder 1 wherefrom it is discharged out of the spout (not shown).

On the down stroke of the body portion 17, the spool 21 becomes unseated from the outlet opening 18 a sufficient distance to permit the upward flow of the water through the working valve. On the further downward movement of the body portion 17, the top of the cage 20 will engage the top of the spool 21 and move the same downwardly, simultaneously causing the rod 22 to move downwardly through the standing valve 2 so that the lower end of the rod will move downwardly within the tubular sleeve 9.

On the upstroke of the working valve 16, the spool will be seated on the top of the head 17 thus closing the outlet opening 18 and when the shaft or rod 25 is moved upwardly in the cylinder 1, a suction will be created in the lower portion of the cylinder between the standing valve and the working valve sufficient enough to cause the unseating of the spool 13 so that the water will rush into the cylinder through the inlet 6 and will enter the chamber between the standing valve and the working valve through the outlet 5 thus forming a column of water in said chamber which column will be ejected out through the working valve

when the latter is operated in the manner shown in Figure 1.

In this manner, water may be lifted upwardly from a deep well in a comparatively simple and efficient manner and the device will at all times be positive in its operation.

The simplicity in which my improved pump valve is constructed enables the parts to be readily assembled or disassembled, and may furthermore be manufactured at a very low cost.

While I have shown the preferred embodiment of my invention it is to be understood that minor changes may be made in the invention without departing from the spirit of the invention and the scope of the appended claims.

Having thus described the invention, what I claim as new and desire to secure by Letters Patent is:

1. A pump valve comprising in combination, a cylinder, a standing valve arranged in the lower portion, a working valve arranged in the cylinder above the standing valve, a water chamber formed between the valve, each of said valves comprising a body having an inlet at its bottom and an outlet at its top, a closure associated with each of said outlets, a cage associated with the top of each body for limiting the upward movement of said closure, said closure being normally seated on the outlet of the standing valve, the closure being seated on the outlet of the body of the working valve when the latter is raised, a rod extending upwardly through the standing valve and said working valve, the closure associated with the working valve being secured on the upper end of the rod, the closure associated with the standing valve being adapted to slide freely on the lower portion of the rod.

2. A pump valve comprising in combination, a cylinder, a standing valve arranged in the lower portion, a working valve arranged in the cylinder above the standing valve, a water chamber formed between the valve, each of said valves comprising a body having an inlet at its bottom and an outlet at its top, a closure associated with each of said outlets, a cage associated with the top of each body for limiting the upward movement of said closure, said closure being normally seated on the outlet of the standing valve, the closure being seated on the outlet of the body of the working valve when the latter is raised, a rod extending upwardly through the standing valve and said working valve, the closure associated with the working valve being secured on the upper end of the rod, the closure associated with the standing valve being adapted to slide freely on the lower portion of the rod, and a guide sleeve for the lower portion of said rod.

3. A pump valve comprising in combination, a cylinder, a standing valve arranged

in the lower portion, a working valve arranged in the cylinder above the standing valve, a water chamber formed between the valve, each of said valves comprising a body 5 having an inlet at its bottom and an outlet at its top, a closure associated with each of said outlets, a cage associated with the top of each body for limiting the upward movement of said closure, said closure being normally seated on the outlet of the standing valve, the closure being seated on the outlet of the body of the working valve when the latter is raised, a rod extending upwardly through the standing valve and said working valve,

the closure associated with the working valve 15 being secured on the upper end of the rod, the closure associated with the standing valve being adapted to slide freely on the lower portion of the rod, and a tubular member adapted for slidable movement through 20 the standing valve, the upper end thereof being secured to the closure associated with the standing valve, said tubular member forming a guide for receiving the lower portion of said aforementioned rod. 25

In testimony whereof I affix my signature.

GROVER NEGLEY KING.
